UNITED STATES PATENT OFFICE.

JOHN F. MEIGS AND EMIL GATHMANN, OF SOUTH BETHLEHEM, PENNSYLVANIA, ASSIGNORS TO BETHLEHEM STEEL COMPANY, OF SOUTH BETHLEHEM, PENNSYLVANIA, A CORPORATION OF PENNSYLVANIA.

ARMOR-PIERCING PROJECTILE.

No. 806,820.

Specification of Letters Patent.

Patented Dec. 12, 1905.

Application filed June 23, 1904. Serial No. 213,835.

To all whom it may concern:

Be it known that we, JOHN F. MEIGS and EMIL GATHMANN, citizens of the United States, and residents of South Bethlehem, Northampton County, State of Pennsylvania, have invented certain new and useful Improvements in Armor-Piercing Projectiles, of which the following is a specification.

The present invention comprises improvements in the explosive projectile for which Letters Patent No. 753,504 were granted to us March 1, 1904. In this class of projectiles, which are intended for piercing armor, the shock and resulting strain on impact tends to upset and bulge or "barrel out" the cylindrical wall of the projectile, and thus reduce its penetrating effect. This upsetting is greater or less, depending upon the mass to the rear of the zone under the highest strain, which mass comprises the wall surrounding the cavity and the rear end or base of the projectile. In the patented projectile it was sought to give the wall of the shell a maximum columnar strength for a given weight of metal and also to lighten the base.

The present invention comprises means whereby the base of the projectile may be made stronger with a given weight of metal and without materially reducing the capacity of the cavity for explosive material, thus decreasing the liability of the projectile to upset or bulge on impact.

The invention also comprises the combination of a shell having a strengthened base, with a rifling-band located substantially at the base and away from that part of the wall which is liable to upset, thus leaving the said portion of the wall of maximum thickness and strength.

Our invention will be described in connection with the accompanying drawings, in which—

Figure 1 is a longitudinal central section of an explosive projectile embodying the invention. Figs. 2 and 3 are sections respectively on the lines 2 2 and 3 3 of Fig. 1, and Fig. 4 is a sectional view looking toward the base of the projectile from the line 4 4 of Fig. 1.

Referring to the drawings, 10 indicates a shell having the usual cylindrical body and conical point. The cavity of the shell is non-circular in cross-section, having, as shown, inwardly-projecting ribs or stiffeners 11. These ribs or stiffeners may be of various

cross-section—as illustrated, for instance, in the patent referred to. The base 12 of the shell is preferably rounded internally, so that a section of the same is in the form of a flat arch, which form is strong in proportion to the metal employed. In order to reduce the metal in the base to a minimum consistent with the strength required, ribs or stiffeners 13 are provided on the inner surface of the base, these ribs or stiffeners serving the purpose of brackets to support the base. As shown, the stiffeners 11 and 13 are continuous, which is the preferred form, although it will be evident that they may be separate and the numbers of each may be different in a given shell. The preferable construction, however, is that shown in the drawings, in which continuous ribs 11 13 extend from the forward end of the cavity to the central opening 14, which is provided in the base for the fuse. The groove in the shell, which receives the rifling-band, tends to weaken the wall of the shell and create a zone which would be liable to buckle or upset. To prevent this, the present invention includes placing the rifling-band 15 at the extreme rear of the wall of the shell and substantially where the wall merges with the base. On account of the lightness and stiffness of the base, due to the ribbed construction already described, upsetting of the shell at the rifling-band groove is effectually prevented by locating the rifling-band as described. The ribs or stiffeners 11 preferably converge toward the forward part of the shell, as shown, to stiffen the forward arch. A boss 16 is preferably provided on the base of the shell, either on the inside or on the outside, in order to give sufficient thickness to receive the fuse.

It will be evident that the invention may be embodied in various forms other than that shown in the drawings. For instance, the ribs 13 may be separate or disconnected from the ribs 11, and either or both sets of ribs may be of any of the various sections shown in our Patent No. 753,504 or of other equivalent sections.

Therefore, without limiting ourselves to the precise construction illustrated and described, we claim—

1. A projectile having a central cavity surrounded by a cylindrical wall, a conical point

and a base, and having inwardly-projecting ribs or stiffeners on said cylindrical wall and base.

2. A projectile having a central cavity surrounded by a cylindrical wall, a conical point and an internally-arch-shaped base, and having inwardly-projecting ribs or stiffeners on said cylindrical wall and base.

3. A projectile having a cylindrical wall and a base and a central cavity, and having said wall and base supported by internal ribs or stiffeners, the ribs or stiffeners of the base being continuous with those of the cylindrical wall.

4. A projectile having a cylindrical wall, and a base provided with internal ribs or stiffeners, and having a rifling-band located at the base surrounding the rear thickened end of the projectile, for the purpose set forth.

In testimony whereof we have signed our names to this specification in the presence of two subscribing witnesses.

JOHN F. MEIGS.
EMIL GATHMANN.
